A technical drawing of a mechanical assembly, possibly a hinge or joint mechanism, with two numbered callouts. Callout 9 points to a top part, and callout 10 points to a lower part. To the right of the drawing, the word 'Inventor' is written above the handwritten name 'E. E. Norquist'. Below the drawing, the word 'Attorney' is written above the handwritten signature 'George J. Thorpe'.

UNITED STATES PATENT OFFICE.

EMANUEL E. NORQUIST, OF KANSAS CITY, MISSOURI.

SHEET-METAL GARAGE.

1,325,855.

Specification of Letters Patent. Patented Dec. 23, 1919.

Application filed December 27, 1915. Serial No. 68,939.

To all whom it may concern:

Be it known that I, EMANUEL E. NORQUIST, citizen of the United States, residing at Kansas City, in the county of Jackson 5 and State of Missouri, have invented certain new and useful Improvements in Sheet-Metal Garages, of which the following is a specification.

This invention relates to knock-down sheet 10 metal garages and the like, and has for its object to produce an arched roof garage which can be manufactured cheaply, shipped in knock-down condition and easily and quickly erected by unskilled labor.

With this general object in view, the invention consists in certain novel and peculiar features of construction, and combination of parts as hereinafter described and claimed, and in order that it may be fully understood 20 reference is to be had to the accompanying drawings, in which—

Figure 1, is a front view of a round roof garage embodying my invention, one half of the door frame being shown in vertical section and the corresponding door omitted.

Fig. 2, is a horizontal section taken on the line II—III of Fig. 1.

Fig. 3, is an enlarged fragmentary section taken inside the door opening and looking 30 forward.

Fig. 4, is an enlarged section taken on the line IV—IV of Fig. 3.

Fig. 5, is a fragmentary side view of a portion of the garage to show the connection 35 between the plates forming the body of the garage.

Fig. 6, is a section taken on the line VI—VI of Fig. 5.

Fig. 7, is a section on the line VII—VII 40 of Fig. 5.

Fig. 8, is an enlarged horizontal section of the left hand front corner of the garage taken in the same plane as Fig. 2.

Fig. 9, is an enlarged horizontal section 45 of one of the rear corners of the garage.

In constructing the garage which is preferably a little wider than it is high and of substantially inverted-U shape in cross section, the body portion is composed of two 50 side members 1—1, and an arch member 2, connecting the upper ends of the side members. Said members are composed of sheet metal plates 3 formed at suitable intervals

with corrugations 4, preferably of varying width as shown in Fig. 5. There may be 55 any suitable number of plates 3, and they are formed at their meeting edges with narrow corrugations 5, those of adjacent plates being nested and secured together by fastening devices 6. The outer margins of the 60 endmost plates 3 are bent outwardly and doubled back sharply to form grooved ribs 7.

The plates 3 of the arch member are bowed outward on a horizontal line at 8 to receive the correspondingly outward bowed portions 65 9, at the upper ends of members 1, this construction adding to the rigidity and strength of the body portion and facilitating the shedding of water therefrom.

Fastening devices 10, such as bolts and 70 nuts extend through the members 1 and 2 at the points where the portions 8 and 9 are intersected by the corrugations 4. The back wall 11 of the garage is of sheet metal sections 12 stiffened and braced by strips 13, 75 securing devices 14, such as bolts and nuts, extending through the strips and sections to secure said parts together.

The edge of wall 11 fits in the grooved portions 7 of the body portion as shown 80 clearly in Fig. 2. Preferably the back wall will be provided with a window 15.

The front wall is composed of two vertically disposed side segment plates 16, and an upper segment plate 17, the latter having 85 downwardly diverging extensions 18 of reduced width which abut endwise against the upper end of the sections 16 and said plates are secured together by reinforcing plates 19.

The outer margins of the plates 16 and 17 90 fit into the front grooves 7 of the body portion and are fastened rigidly thereto as at 20 by bolts and nuts, similar bolts and nuts, not shown, fastening the margins of the back wall in the grooves 7 at the rear end of the 95 body portion.

The back wall and the front wall are similarly stiffened and strengthened by corrugations 21, adjacent to and parallel with the margin of the body portion and to 100 further stiffen and strengthen the front wall the upper plate 17 is connected to the side plates 16 by downwardly diverging angle bars 22, the same being arranged like reinforce plates 19 at the inner side of the 105 front wall, as shown in Figs. 3 and 4. To

hold the garage in shape its side walls and back wall rest upon and are secured to angle bars 23 and 24 respectively.

The space between plates 16 and below plates 17, constitutes the door opening, and it will be noted that between the extensions of plate 17, the door opening is narrowed, that is to say the upper corners for the door opening are omitted for a reason hereinafter explained. A door frame cut away at its upper corners is constructed as follows:

25 is a bottom tube arranged at the lower end of the door opening and projecting beyond the sides thereof, the projecting portions having vertical slits 26 receiving the lower ends of the side plates of the front wall. 27 are vertical tubes welded at their lower ends to tube 25 at the inner ends of the slits 26 thereof, and said vertical tubes 28 have slits 28 receiving the inner edges of said side plates 16. 29 are upwardly converging tubes welded at their lower ends to the upper end of tubes 27 and provided in their outer edges with slits 30 receiving the inner edges of extensions 18 of plate 17. 31 is a horizontal tube forming the top of the frame and connecting the upper ends of the tubes 29 and provided with a slit 32 receiving the lower edge of the top plate 30 17 of the door opening. A frame constructed as described can be slid into engagement with the marginal portions of the door opening, and to hold the frame in such relation the vertical side tubes 27 and the top tube 31 are provided with lugs 33 to fit against opposite sides of the adjacent portions of the front wall and with fastening devices 34 such as bolts and nuts to extend through said lugs and the interposed portions of the front wall.

35 are doors hinged at 36 to the sides of the front wall and adapted to close against the tubing door frame. Above the door is a guard or shield 37 projecting from the upper member of the front wall and adapted to prevent rain from beating in at the upper ends of the doors, and above said guard is a ventilator 38. The garage is not shown as provided with a floor though it may be provided with one, if desired.

As the top of a motor car is considerably narrower than the space between the outer margins of the wheel fenders, it is possible to house a car in an arched roof garage 55 which is relatively smaller than one of any other style in which the same car can be housed. An arched roof garage for a car requiring a door opening of proportionately the width shown in Fig. 1, would not accommodate a car of slightly less height than the door shown if the upper corners of the door were not cut away and the tubing angled upwardly and inwardly to conform somewhat to the curvature of the roof. The 60 angling upward of the door frame is there-

fore of great practical importance as it lessens the amount of material required for the body and materially reduces the cost of manufacture and permits the garage to be sold at a price lower than possible with door frames lacking the cut away corners. 70

With this garage no special foundation is needed but it is desirable to provide four-by-fours arranged externally at the sides and back as a means of support or anchorage for the angle bars 23 and 24. The four-by-fours are not shown as they form no special part of the structure and other means such as stakes, not shown, may be provided to anchor the angle irons securely in place. 80 A garage of the type described is fireproof and affords thorough protection from the elements and thieves. Any suitable locking means, not shown, may be employed to secure the doors in closed position. 85

From the above description, it will be apparent that I have produced a garage possessing the features of advantage enumerated as desirable in the statement of the object of the invention and I wish it to be understood that while I have illustrated and described the preferred embodiment of the invention I reserve the right to make all changes falling within the spirit and scope of the appended claims. 90

I claim:

1. In a sheet metal garage, a doorway frame comprising side portions, a top provided with downwardly diverging extensions secured to the upper ends of the side portions and a door frame consisting of a bottom tube provided with slits in the upper side of its ends receiving the lower ends of said side portions, upright tubes provided with vertical slits in their outer sides receiving the inner edges of said side portions, short tubes converging upward from the upper ends of the side tubes and provided with slits in their outer sides receiving the inner edges of said extensions of the top portion and an upper tube connecting the ends of said upwardly converging tubes and provided in its upper side with a slit receiving the lower edge of the said top portion between the extensions thereof. 105

2. In a sheet metal garage, a doorway frame comprising side portions, a top provided with downwardly diverging extensions abutting against the upper ends of the said side portions, reinforce plates bridging the joint between said portions and secured thereto, and brace bars also bridging said joint and secured to said side portions and upper portion and extending in the same general direction as the said extensions of the top portion, and a door frame consisting of a bottom tube provided with slits in the upper side of its ends receiving the lower ends of said side portions, upright tubes provided with vertical slits in their 110 120 125 130

outer sides receiving the inner edges of said side portions, short tubes converging upward from the upper ends of the side tubes and provided with slits in their outer sides receiving the inner edges of said extensions of the top portion and an upper tube connecting the ends of said upwardly

converging tubes and provided in its upper side with a slit receiving the lower edge of the said top portion between the extensions thereof.

In testimony whereof I affix my signature.

EMANUEL E. NORQUIST.
